(57) **CLAIM**

The ornamental design for a digital camera with display screens having graphical user interfaces, as shown and described.

DESCRIPTION

FIG. 1 is a top, rear and left side perspective view of a digital camera with display screens having graphical user interfaces showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is an annotated, enlarged detail view of the camera body display screen thereof, shown separately for clarity of illustration;

FIG. 9 is an enlarged detail view of the area defined by lines IX-IX of FIG. 8; and,

FIG. 10 is a rear elevational view of a second embodiment of the digital camera with display screens having graphical user interfaces in which the graphical user interface described in FIG. 8 is displayed on the camera body display screen and on the viewfinder display screen.

The broken line showing of the digital camera, display screens and remaining areas of the graphical user interfaces forms no part of the claimed design.

The dash-dot broken lines in FIG. 9 define the bounds of the claimed design and form no part thereof.
